(57) **CLAIM**

The ornamental design for a clasping stability device, as shown and described.

DESCRIPTION

FIG. 1 shows a front-facing perspective view of a clasping stability device showing my new design;
FIG. 2 shows a rear-facing perspective view thereof;
FIG. 3 shows a left-side elevation view thereof;
FIG. 4 shows a right-side elevation view thereof;
FIG. 5 shows a front elevation view thereof;
FIG. 6 shows a rear elevation view thereof;
FIG. 7 shows a top plan view thereof;
FIG. 8 shows a bottom plan view thereof;
FIG. 9 shows a top plan view thereof in a clasping state;
FIG. 10 shows a bottom plan view thereof in the clasping state;
FIG. 11 shows a rear-facing perspective view thereof in an open state;
FIG. 12 shows a rear-facing perspective view thereof in a clasping state;
FIG. 13 shows an environmental view of the clasping stability device attached to a hand truck;
FIG. 14 shows an environmental view of the clasping stability device attached to the hand truck in an open state;
and,
FIG. 15 shows an environmental view of the clasping stability device attached to the hand truck in a closed state. The broken lines depict portions of the clasping stability device that form no part of the claimed design. The unclaimed material in FIGS. 11 and 12 is shown transparent for ease of illustration of internal mechanisms. The broken lines in FIGS. 13, 14, and 15 additionally depict environmental structure that forms no part of the claimed design.

1 Claim, 9 Drawing Sheets
